DOORLOCK

Filed May 14, 1925

UNITED STATES PATENT OFFICE

JOHN HOLTZMAN, OF NEW YORK, N. Y.

DOORLOCK

Application filed May 14, 1925. Serial No. 30,177.

This invention relates to combined key and knob actuated locks, such as are used on the doors of buildings to attain exceptional safety.

5 One of the objects is to provide a lock embodying a curved bolt, pivoted at its axis within the lock casing, to engage with a pair of spaced keeper lugs in an unusually secure manner.

10 It is a further feature to produce a lock having an arcuate bolt movable in a circular path, and which, when in an engaged position, cannot be retracted by other than its key or knob, except by actual rupture of its

15 parts.

Another aim is in the provision of an essentially inexpensive lock comprised of few and simple parts, not readily liable to become disordered, proportioned to provide 20 adequate strength and present an attractive appearance.

These and other approved features are accomplished by the present construction and combination of elements hereinafter described and illustrated in the associated drawings, constituting a material part of this disclosure, and in which:

Figure 1 is a partial bottom plan and partial sectional view of a lock made in accordance with the invention, the section being taken on line 1-1 of Figure 2.

Figure 2 is a longitudinal sectional view of the same, taken on line 2-2 of Figure 1, showing its application.

35 Figure 3 is a plan view of the lock as engaged with its keeper.

In the drawings the numeral 10 designates a fragmentary portion of a door and 11 the casing jamb thereof, this jamb having rigidly 40 secured to it a keeper plate 12 having a right angled flange 13 set in the front edge of the jamb and fastened by screws 14.

The keeper is of considerable length to admit of firm engagement and is provided with 45 a pair of outstanding integral lugs 15 arranged in spaced angular relation, as shown best in Figure 3, these keeper lugs having circular openings 16, and their outer surfaces are curved to a radius from the centers of 50 the openings.

The lock is composed of a hollow body having an outer plate 17, containing a depressed panel 18, side walls 19, joined by a straight right angled rear wall 20 and a thickened arcuate front wall 21, which is also curved transversely to present a hollow semi-circular extending portion terminating in a flange 22 level with the edges of the side and rear walls.

Rising centrally from the casing plate 17 60 is an integral post 23 fitted to receive a screw 24 in its outer end by which is secured a plate 25 covering the open under side of the casing.

The casing body is secured by screws 26 65 passed through opening 27 in the plate 17 as usual.

A raised surface finished boss 28 is disposed centrally on the plate 17, at the axis of the curved front 21 and revolvably mounted on a stud 29 set therein is a hub 30 having an extending arm 31, carrying a curved bolt 32 of circular cross section, this bolt being freely movable within the curved space bounded by the wall 21.

In the curved front portion of the lock casing are a pair of spaced radial openings 33, receptive of the lugs 15, the bolt, when in an engaged position, passing through the openings 16 in both of the lugs constituting 80 an unbroken bar member, positively securing the lock casing to the keeper in an unusually effective manner.

A stop pin 34 is set in the outer wall of the casing to limit the travel of the arm 31 85 when in a forward position.

Motion is communicated to the bolt by means of a thin flat link 35 pivoted by a crank pin 36 to the hub 30 at a point offset to its center, the other end of the link being 90 similarly pivoted by a pin 37 to a block 38 slidably mounted on a rod 39 set in grooves 40 and 41 formed respectively in pads 42 and 43 integral with the casing plate 17, adjacent one side of the lock, as best shown in 95 Figure 1.

Extending from the block 38, towards the center of the casing, are a pair of spaced lugs 44 having adjacently bevelled surfaces inclined towards a central recess 45.

A hollow boss extends outwardly from the center of the panel 18, near the rear portion of the lock casing, and revoluble therein is a sleeve 47 having an opening and fixed at the outer end of the sleeve is the hollow hub 46 of knurled knob 50, this hub being seated on the boss with which it corresponds. A thin flat rectangular stem 48 is guided in the opening of the sleeve 47 and hollow hub 16 and is freely rotatable therein.

Fixed on the inner projecting end of the sleeve is a washer-like plate 51 having diametrically opposed arms 52 and 53 in which are secured headed studs 54 normally maintained in the central longitudinal plane of the casing by reason of their contact with the arm 55 of a spring 56 coiled around a pin 57 fixed in a pad 58 on the inner surface of the casing plate 17, another arm 59 of the spring being seated against the casing rear wall 20.

It will now be seen that upon rotating the knob 50, in clock-wise direction, the arm 53 will engage the rear lug 44, causing the block 38 to slide on the rod 39, and, due to the link connection 35, retract the bolt 32 from the keeper lugs, by rotating it on the pivot 29.

Obviously a reverse movement of the knob 30 will cause the bolt to move into an engaging position.

The opposite end of the stem 48 is held in a conventional cylinder lock 60, set in the door 10 and actuated by a key 61, the lock 35 being held by the usual fastening means as shown and may be of preferred type.

In order to positively retain the bolt in locked or unlocked position, the hub 30 is provided in its periphery with two notches 40 62 and 63, engageable with either of which is a detent 64 carried at the end of an arm 65, pivoted on a pin 66 near the rear of the lock casing, this detent arm being pressed inwardly against a limit pin 67 by a pair of opposed 45 leaf springs 68 located by a pin 69, one of the leaves making contact with the side wall of the casing and the other bearing against the arm 65.

Immediately prior to movement of the block 38 by the arm 53, the opposite arm 54 engages the inner surface of the detent arm 65, withdrawing the detent from the notch 62 and further rotation of the stem 48, either 55 by the knob 50 or key 61, releases the detent to engage the notch 63 in a manner that will be clearly apparent, thus securing the bolt in either of its adjusted positions.

In order to operate the bolt by the key a 60 plate 70 is fixed on the inner side of the door, adjacent the lock casing plate 25, in which latter plate is revolvably mounted a sleeve 71.

Fixed on the sleeve 71 is a lever 72 having 65 at one end a raised offset finger 73 adapted

to engage the lugs 44 and thereby move the block 38 in actuating the bolt by the key.

In this type of cylinder lock, the key 61 must make a full rotation before it can be removed from the lock, and in order to permit the lever to complete a full revolution, an opening 74 is formed through the arm 65 allowing the finger 73 to pass as it is rotated by turning the key.

From the foregoing it will be seen that a simple device for this purpose has been disclosed in the preferred form of its embodiment, but it is not desired to restrict the details to the exact construction shown, it being obvious that changes, not involving the exercise of invention, may be made without conflicting with the scope of the appended claims.

Having thus described my invention, what I claim as new and desire to secure by Letters Patent, is:—

1. A lock having a single curved bolt adapted to move in an arcuate path and mechanism to operate said bolt including the combination of a carriage adapted to move rectilinearly in opposite directions, key operated means to actuate said carriage, a link connecting said carriage to said bolt to transmit motion to said bolt, and a pawl adapted to engage said bolt to lock it in its operative and inoperative positions, said key means operating said pawl to release said bolt prior to the actuation of said carriage.

2. A lock having a single curved bolt adapted to move in a curved path, and mechanism to operate said bolt including the combination of a carriage movable rectilinearly in opposite directions, a bar disposed parallel to the direction of movement of said carriage passing therethrough to guide it in its movement, key operated means to actuate said carriage, a link on said carriage to transmit motion to said bolt, and a stop limiting the movement of the bolt.

3. A lock having a single curved bolt movable in an arcuate path, and mechanism to operate said bolt including a carriage movable rectilinearly in opposite directions, a bar passing through said carriage to guide it in its movement, a pair of lugs on the lock casing having notches, said bar having its terminals lodged in said notches to be held thereby, key operated means to actuate said carriage, and a link joining said carriage to said bolt to transmit motion therebetween.

4. A lock having a bolt and mechanism to operate said bolt including a carriage adapted to move in opposite directions, a guide bar passing through the carriage, key operated means to actuate said carriage, a link to transmit motion to said bolt from said carriage, and a fixed stop for said bolt.

5. A lock having a bolt and operating mechanism therefor including a carriage movable in opposite directions, a bar on

which said carriage is mounted to guide it in its movement, a pair of lugs integral with the casing of said lock having notches, said bar being held by said notches, key operated means to actuate said carriage, and a link operatively joining said carriage to said bolt.

6. A lock having a bolt and mechanism to operate said bolt including a carriage movable in opposite directions, key operated means to actuate said carriage, a link joining said carriage to said bolt to transmit motion to said bolt, and a pawl to lock said bolt in its operative and inoperative state, said key means operating said pawl to release said bolt prior to the actuation of said carriage.

7. In a lock the combination of a keeper having projected bolt retaining means, a lock casing, a curved bolt mounted in said casing, the casing having a cut-out portion adapted to straddle the bolt retaining means of the keeper, said bolt passing through the cut-out portion of the casing when in locked position and out of said portion when unlocked, key operated mechanism to operate said bolt, a stop for said bolt, a spring impelled detent to retain said bolt in either of its extreme positions, said detent having an opening permitting the passage of a part of said key mechanism, and means on said mechanism to retract said detent prior to shifting said bolt.

8. A lock having a single bolt of cylindrical cross section, mechanism to operate said bolt including the combination of a carriage adapted to move in opposite directions, a removable guide rod disposed in the direction of movement of said carriage passing therethrough to guide it in its movement, key operated means to actuate said carriage, and a link joining said carriage to said bolt to transmit motion to said bolt.

9. A lock comprising a casing having a protruding, arcuate front end, a curved bolt operable therein, means to actuate said bolt into either locked or unlocked position, a spring detent to retain said bolt in either position, said actuating means including a reciprocative block, a double ended member to move said block, a spring detent for said member, and a knob to rotate said member.

10. A lock comprising a casing having a protruding, arcuate front end, a curved bolt operable therein, means to actuate said bolt into either locked or unlocked position, a spring detent to retain said bolt in either position, said actuating means including a reciprocative block, a double ended member to move said block, a spring detent for said member, manually operable means to operate said member, and means on said member to retract the first named spring detent prior to moving said bolt.

11. In a lock comprising a casing, a keeper, lugs projecting from said keeper, said casing having openings at one end thereof and arranged to straddle said lugs, a bolt rotatably

mounted in said casing arranged to pass through said lugs when in operative state, said bolt comprising a hub having a pair of cut-out notches, an arm connecting said hub and bolt, mechanism to operate said bolt, said mechanism including a link pivotally connected to said hub at one end, a pivotally mounted pawl arranged to register with one of the notches of said hub at one time and with the other at another time, a double ended member rotatably mounted in said casing and arranged with one end to actuate the pawl to release the bolt from locking engagement with said pawl and with its other end to operate the link for transmitting rotary motion to said bolt, and manually actuated means to operate said member.

12. A lock having a casing, a single curved bolt adapted to move in a curved path mounted in said casing, mechanism to operate said bolt including the combination of a carriage movable in opposite directions, stationary means fixed in said casing to guide said carriage in its movement, a pawl pivotally mounted in said casing to lock said bolt in its operative and inoperative positions, a double ended member mounted in said casing to operate said carriage for transmitting rotary motion to said bolt and arranged with one end to operate said pawl to release said bolt prior to the actuation of said carriage and with its other end to move said carriage, manual means to turn said member, another element rotatably supported in said casing to reciprocate said carriage and a key operated mechanism extending from the casing to turn said element.

13. A lock comprising a casing, a curved bolt having a hub pivoted in said casing, means to actuate said bolt into either locked or unlocked position, a spring operated detent to retain said bolt in either position and having an opening, said actuating means including a link pivotally connected to the hub of said bolt, a double ended member, one of the ends of said member having an offset for transmitting a reciprocatory motion to said link to operate said bolt and arranged to actuate said detent prior to the actuation of said link, and key operated means to rotate said member, said opening in the spring operated detent enabling the member with its offset to make a complete revolution.

14. In a lock, the combination of a casing, a keeper having a projecting lug, an opening formed in said lug, said casing having a cut-out portion at its front end to straddle said lug, a curved bolt rotatably mounted in said casing arranged to pass through the opening of the lug when in locked state and out of the opening when unlocked, mechanism to operate said bolt, said mechanism comprising a link pivotally connected to said bolt, a pawl mounted in said casing to lock said bolt at its hub part when said bolt is

in operative or inoperative state, a double ended member rotatably mounted in said casing having one of its ends offset and arranged to be manually rotated to operate said pawl with one end and actuate the link with its other end for transmitting a rotary motion to said bolt, and means outside of the casing to operate said member.

15. In a lock, the combination of a keeper having projecting bolt retaining means, a lock casing, a curved bolt mounted in said casing, said casing having a cut-out portion adapted to straddle the bolt retaining means of the keeper, said bolt passing through the 20 cut-out portion of the casing when in locked position and out of said portion when unlocked, mechanism to operate said bolt, said mechanism comprising a link having a pivot connection with said bolt for transmitting a 25 rotary motion to the bolt, a pawl to lock said bolt at the hub part at its operative and inoperative positions, a double ended member mounted in said casing to transmit a combined reciprocatory and oscillatory motion to said link and arranged with one end to operate the pawl to release the bolt and with the other end actuate said link, and manually operable means to rotate said member.

In testimony whereof I have signed my 20 name to this specification.

JOHN HOLTZMAN.
